(57) **CLAIM**

The ornamental design for an electronic connector and aperture plug, as shown and described.

DESCRIPTION

FIG. 1 is a front perspective view of a first embodiment of an electronic connector and aperture plug showing my new design;

FIG. 2 is a side elevation view thereof;

FIG. 3 is a rear perspective view thereof;

FIG. 4 is a front perspective view of a second embodiment of an electronic connector and aperture plug showing my new design;

FIG. 5 is a side elevation view thereof; and,

FIG. 6 is a rear perspective view thereof.
